KEDGE ANCHOR

Filed April 2, 1928

INVENTOR:
Charles A. Mansell,
BY
M. B. Martens
His ATTORNEY.

UNITED STATES PATENT OFFICE

CHARLES A. MANSELL, OF CINCINNATI, OHIO

KEDGE ANCHOR.

Application filed April 2, 1928, Serial No. 266,500, and in Newfoundland March 8, 1928.

This invention relates to kedge anchors particularly of the type which are suitable as an anchorage for fishing traps, fishing trawls or other light boats and the like and has for its particular objects the provision of a construction which is highly effective as an anchorage and enables one to readily kedge a vessel from place to place while at the same time such anchor can be readily raised or lowered without necessitating a large crew of men as is now commonly required for this purpose.

In the accompanying drawings in which I have illustrated a preferred embodiment of my improved kedge anchor,

Figure 1 is an elevation;

Fig. 2 is a vertical section partly in elevation;

Fig. 3 is a top plan view and

Fig. 4 is an elevation showing the anchor just prior to the same being hoisted from the bottom of a bay or harbor.

Referring to the drawings and construction shown therein, the reference numeral 1 designates a weighted base or block preferably comprising a solid metal casting having projecting lugs or prongs 2 to which is secured a hollow casing 3 preferably of pyramidal shape. Said casing is provided with sliding gate or slide member 4 which, when in the position shown in Fig. 2 is adapted to completely close said casing, so as to prevent the escape therefrom of filling material, such as stones, sand or gravel with which the casing shall have been filled prior to anchor being dropped. Said gate is provided with a ring or eye 5 to which is secured an operating rope 6, whereby said slide may be opened to any desired extent, or as shown in Fig. 4, completely removed, if desired, in order to permit the escape of the filling material, such as above specified when it is desired to hoist the anchor. A rod 7 having an upper terminal eye 8 is secured to the head or base 1 and a hoisting rope or line 9 which is secured to said eye permits of the hoisting of the anchor after the slide has been opened or removed as aforesaid.

While I prefer to construct the casing of the plurality of triangular sheets having

struck-up flanges *a*, the contacting flanges of the adjacent sheets being secured to each other by rivets *b* and to rigidly secure said sheets to said head either by casting the head around the lower ends of the same and around the lower ends of the rod 7 as illustrated in Fig. 2, or otherwise securing the same to said head or base 1, nevertheless, said casing may be constructed of a continuous sheet of metal and may be conical in configuration or may be of such other desired construction or shape as is embraced within the scope of the appended claims.

In order to guide the slide 4, I preferably provide angle iron members 10, 10' which, as shown, are riveted to the upper ends of the opposing sides *c*, *c'* of said casing.

The aforesaid construction constitutes an anchor which is extremely mobile, even though extremely large and when loaded, unusually heavy, and the same may be readily handled by a single fisherman or operator, since it is merely necessary before such operator drops the same to shovel thereinto some sand or gravel carried in the boat for this purpose, then insert the slide so that the bottom of the same rests against the top of the base 2, as shown in Fig. 2, and thereafter proceed to allow the same to be dropped overboard to the desired spot of anchorage. The hoisting rope 9 is provided on its upper end with a buoy (not shown) which serves the purpose of locating the anchor when the same is used as a permanent anchorage for fishing traps or for other purposes. When it is desired to hoist the anchor, the operator first pulls on the rope 9 in order to raise the anchor to a vertical or substantially vertical position, such as shown in Fig. 4, so as to admit of the easy removal of the slide and then by means of the rope 6, either removes the slide or opens the same sufficiently to admit of the water washing out the gravel or sand as the anchor is then raised through the water by the operator who then hoists the empty casing to the surface by means of the rope 9.

Various modifications within the scope of the appended claims may be made without departing from the spirit of my invention.

What I claim and desire to procure by United States Letters Patent is:

1. In a kedge anchor, the combination comprising a receptacle of varying cross sectional area from top to bottom and being of smallest cross sectional area at its bottom and said receptacle being adapted to be weighted with filling material and having an extensive lateral opening, closure means for optionally closing said opening, means for opening said closure means from a distance and means for hoisting said anchor.
2. In a kedge anchor, the combination comprising a receptacle of pyramidal cross section and having an extensive lateral opening, said receptacle being adapted to be weighted with filling material, closure means for optionally closing said opening, means for opening said closure means from a distance and means for hoisting said anchor.
3. In a kedge anchor, the combination comprising a pyramidal receptacle having a weighted base rigidly secured to its smallest end, said receptacle being adapted to be weighted with filling material and having a sliding door constituting one of its sides, opposing guides for preventing the accidental displacement of said door, means for hoisting said anchor and separate means for opening said door prior to hoisting the anchor completely to the surface of the water.
4. In a kedge anchor, the combination comprising a base, a closed receptacle being adapted to be weighted with filling material, supported on said base, said receptacle and said base being cast integral with each other, hoisting means for raising said anchor and means for opening said receptacle and permitting the escape of weighted filling material therefrom while the same is submerged in water.
5. In a kedge anchor, the combination comprising a receptacle of pyramidal cross section and having an extensive lateral opening, slideable closure means, a cable secured to said closure means for opening the same from a distance and an anchor rod centrally secured to said anchor for hoisting the same and opposing laterally projecting prongs secured to the bottom portion of said receptacle.

Signed at Cincinnati, in the county of Hamilton and State of Ohio, this 23d day of March, 1928.

CHARLES A. MANSELL.
